By Watson E. Coleman
Attorney

UNITED STATES PATENT OFFICE

MAX H. SCHLYFESTONE, OF PONTIAC, MICHIGAN

AUTO BRUSH

Application filed February 11, 1932. Serial No. 592,370.

This invention relates to cleaning devices and pertains particularly to a brush structure of the fountain type.

The primary object of the present invention is to provide a fountain brush designed for performing various cleaning operations such as automobile body washing, window, floor, building washing or the like, in which a continual water spray is projected onto the bristles of the brush.

Another object of the invention is to provide a brush structure of the character described in which the bristles are mounted in two removable units so that they may be removed and the body of the brush employed as a grass spray or the like.

A still further object of the invention is to provide an auto brush having a water chamber forming a part of the head thereof from which water is ejected through apertures in the walls onto brushes disposed upon opposite sides of the water chamber and removably held in such positions.

Other objects and advantages of the invention will become apparent as the description of the same proceeds and the invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a bottom plan view of the brush structure embodying the present invention;

Figure 2 is a sectional view taken substantially upon the line 2—2 of Figure 1;

Figure 3 is a detail view of a portion of a modified brush head structure;

Figure 4 is a view showing a support for the brush head when using the same as a spray.

Figure 5 is a view in side elevation of the valve element used in association with the

brush, showing the swivel and exteriorly threaded couplings forming a part thereof.

Referring now more particularly to the drawing wherein like numerals of reference indicate corresponding parts throughout the several views, the numeral 1 indicates the head portion of the auto brush embodying the present invention and this head is preferably of the elongated rectangular contour shown. On one side of the head 1 there is formed the longitudinally extending casing 2 which has the side walls 3 which are disposed in V formation, thus forming the casing of substantially triangular cross section, the head portion 1 forming the third side wall therefor. The ends of the casing 2 are closed and the convergent side walls 3 are each provided with the longitudinally extending series of relatively small spray apertures 4.

The width of the water casing or chamber 2 is materially less than the width of the head 1 and as the casing is placed exactly on the longitudinal center of the head it will thus be seen that a portion of the head projects beyond each longitudinal side of the casing. Each of these projecting portions of the head 1 has secured thereto to extend longitudinally thereof, the spaced parallel walls 5. These walls extend from the same side of the head 1 as the casing 2 and are at right angles to the surface of the head.

Mounted between each pair of walls 5 which constitutes a clip, is the base portion 6 of a brush element which is indicated as a whole by the numeral 7. This brush element is of the same length as the head 1 and the bristles 8 which are secured in the base project from the clip and are in position to receive the jets of water escaping from the casing 2 through the apertures 4 when the brush is in operation.

While any suitable means may be employed for securing the brushes in their respective clips there are illustrated two preferred methods one of which consists in passing a screw bolt 9 through suitable apertures formed in the walls 5 of the clips and through an aperture formed in the base 6 of the brush. In Figure 3 there is illustrated another method

of securing the brushes in position. In this method the brush which is here indicated by the numeral 10, has each end wall provided with a notch 11 in which engages the hook portion 12 of a spring tongue 13 which is mounted upon the head of the brush at the end of the clip which is here indicated generally by the numeral 14.

The central portion of the head 1 of the brush has attached thereto and opening therethrough into the water receiving chamber 2, one end of a short pipe-like handle 15, the other end of which has swivelly mounted thereon the threaded coupling 16 by means of which a hose may be connected with the brush.

From the foregoing description it will be readily apparent that when a hose is attached to the free end of the pipe handle 15 and water injected into the casing 2, the water will escape through the apertures 4 in the outwardly facing walls 3 of the casing onto the bristles of the brush elements 8 which are mounted between the walls 5 at the sides of the brush head. The brushes may then be worked over the surface which is to be cleaned and they will be continually supplied with clean water so that the cleaning operation will be greatly facilitated.

In addition to using the device herein disclosed as a cleaning element it may also be employed as a spray for lawns and other purposes. When used as a lawn spray the brush elements or units 7 are removed and the head 35 is turned bottom face upwards and mounted on any suitable support. As an example there is shown in Figure 4 a support which consists of a pair of wire leg members 17 which form the ends of a single piece of wire which at points intermediate the ends is bent to form the bills 18 which are directed toward one another and are in spaced relation with an intermediate portion 19 which connects the legs together and maintains these bills in the spaced aligned relation described and shown.

This support is placed into use by positioning each end of the head 1 beneath a bill 18 so that the head overlies and rests upon the intermediate portion 19 in the manner illustrated and the ends of the legs 17 may then be forced into the ground and will serve to retain the apertured walls 3 of the head water chamber facing upwardly so that the streams of water escaping through the apertures 4 will rise and be directed outwardly in arcuate streams away from the spray head.

While it has been previously stated that a hose may be connected with the tubular handle 15 by means of the coupling 16 it is preferred that there be connected to this coupling a valve unit such as shown and indicated generally by the numeral 20 and the hose conducting the water to the brush may then be joined to this unit. As shown, this

valve unit 20 has the usual body portion 21 in which the rotating element is mounted and at one side it is provided with the extension 22 which carries screw threads upon its outer surface and this extension threads into the swivel coupling 16. At the opposite side of the valve body from the threaded extension 22 there is an interiorly threaded sleeve or cylindrical member 23 which is swivelly connected with the valve body to facilitate its connection with the hose line.

It will be readily apparent that by providing the brush with the valve structure 20, as shown, the user may readily control the flow of water to the brush head as conditions require.

Having thus described the invention, what is claimed is:—

1. An auto brush comprising a head body of elongated design, a water receiving chamber upon and extending longitudinally of one face of the head, said chamber having two rows of oppositely directed water outlet apertures, a pair of brush elements, means forming a part of the body for receiving and removably securing each brush element to said head upon one side of said water chamber to receive the water ejected from one row of apertures, and means for injecting water into said chamber.

2. An auto brush comprising an elongated head body, a water chamber upon and extending longitudinally of one face of the body and having two longitudinal side walls arranged in V formation and each having a longitudinally extending series of water outlet apertures therethrough, a pair of spaced parallel wall members carried by the head at each side of the water chamber and extending longitudinally of the head and constituting a clip, a brush element detachably secured in each clip, and means for injecting water under pressure into said chamber.

3. An auto brush comprising an elongated head body, a water chamber upon and extending longitudinally of one face of the body and having two rows of water outlet apertures arranged to discharge water in opposite directions, a pair of spaced wall members extending longitudinally of the body at each side of said chamber and constituting a clip, a tongue member carried by the head at one end of each clip and having an inwardly extending bill, a brush element mounted in each clip and engaged and detachably held in position by the bill of the adjacent tongue, and means for injecting water into the chamber.

4. An auto brush comprising an elongated head body, a water chamber upon and extending longitudinally of one face of the body and having two longitudinal side walls arranged in V formation and each having a longitudinally extending series of water outlet apertures therethrough, a pair of

spaced parallel wall members carried by the head at each side of the water chamber and extending longitudinally of the head and constituting a clip, a brush element mounted in each clip, a screw element extended transversely through the walls of each clip and through the brush element to removably hold the same in position, and means for injecting water under pressure into said chamber.

In testimony whereof I hereunto affix my signature.

MAX H. SCHLYFESTONE.
